UNITED STATES PATENT OFFICE.

WILLIAM JOSEPH STILL, OF TORONTO, CANADA.

DESIGN FOR AN ELECTRODE-PLATE.

SPECIFICATION forming part of Design No. 32,664, dated May 15, 1900.

Application filed April 16, 1900. Serial No. 13,139. Term of patent 14 years.

To all whom it may concern:

Be it known that I, WILLIAM JOSEPH STILL, a subject of the Queen of Great Britain, residing at the city of Toronto, in the county 5 of York, in the Province of Ontario, Canada, have invented and produced a new and original Design for Electrode-Plates for Storage Batteries or Secondary Batteries, of which the following is a specification, reference being 10 had to the accompanying drawing, forming part thereof.

The drawing represents a perspective view of the electrode-plate.

As shown in the drawing, the leading or 15 material feature of my design consists of a plate with a central plain portion A, having tongues a' , forming a cone, said tongues be-

ing twisted at a' at their base, so as to throw them all on a plane at right angles to the main portion A and the plane of each individual tongue on the horizontal plane. 20

Having described my invention, what I claim as new, and desire to secure by Letters Patent, is—

The design for an electrode-plate as herein 25 shown and described.

In testimony whereof I have signed my name to this specification in the presence of two subscribing witnesses.

WILLIAM JOSEPH STILL.
